UNITED STATES PATENT OFFICE.

LOUIS J. BRUNE, SR., OF NEW ORLEANS, LOUISIANA.

CAR SEAL.

Application filed December 5, 1925. Serial No. 73,519.

The invention relates to car seals, and has for its object to provide a device of this character comprising a looped member having its ends interengaged and disposed in a 5 frangible member, for instance glass and offset bends in the ends of the looped member within the chamber of the frangible member and forming means for preventing the insertion of a tool into the ends of the 10 frangible member for disengaging the interengaging means.

A further object is to provide interengaged hooked members within the chamber of the frangible member for connecting the 15 looped member together, and offset bends on the same sides of the ends of the band as the hooks and forming abutments for preventing insertion of a tool within the frangible member for disengaging the hooks, 20 one of said bends forming means for preventing outward movement of one of the ends of the band. Also to provide struck out lugs in the band adjacent the last named hook for preventing inward movement of 25 said end of the band.

A further object is to provide one end of the band with a reduced portion, on which the chambered frangible member is 30 slidably mounted to a point where its ends can be stamped to shape and then drawn into the chamber of the frangible member before striking out the lugs for preventing longitudinal movement in one direction of 35 said band end.

With the above and other objects in view the invention resides in the combination and arrangement of parts as hereinafter set forth, showing in the drawing, described and claimed, it being understood that 40 changes in the precise embodiment of the invention may be made within the scope of what is claimed without departing from the spirit of the invention.

In the drawing:

Figure 1 is a perspective view of the seal, 45 Figure 2 is a front elevation of the seal, showing the frangible body member in longitudinal section,

Figure 3 is a perspective view of the in- 50 terengaged end of the band.

Figure 4 is a perspective view of one end of the band and the frangible body member, showing the band end in position to be stamped to form.

Figure 5 is a vertical longitudinal sec- 55 tional view through a modified form of seal

showing a modified form of interengaging means.

Figure 6 is a perspective view of the interengaged ends of the form shown in Figure 5.

Referring to the drawing, the numeral 1 designates the band of the seal, which band is provided with a relatively wide portion 2 on which may be stamped any indicia desired, for instance a number and the name of the railroad. The reduced ends 3 of the band extend towards each other and are provided with hooks 4 which are disposed within the chamber 5 of the transparent 65 body member 6, and are interengaged. It will be noted the hooks 4 are opposed in relation to each other, therefore it will be seen that when one of the ends is passed through the open end 7 of the transparent 70 body member 6 and forced over the other hook 4 the hooks will interengage with each other. The ends 3 are provided with offset bends 8, which extend to the sides thereof the same as the hooks, therefore it will be seen 75 that it will be impossible for an unauthorized person to insert a tool into the device and disengage the same. Referring to Figure 2 it will be seen that the offset bend 8 at the inner end of the chamber 5 will prevent outward movement of the adjacent end of the band which extends through the aperture 9 and is relatively tight therein, consequently the hooks 4, after once being hooked, cannot be disengaged. The band end 3 adjacent 80 the aperture 9 is provided with struck out lugs 10 which engage the adjacent end of the body member 2 and prevent movement of the body member 6 to a position where the hooked members 4 will be outside the cham- 85 ber 5.

During the course of manufacture one of the ends 3 is passed through the body member 6 to the position shown in Figure 4, and at which time the portion of the end 3 100 projecting beyond the open end of the body members is stamped to shape, and then drawn into the body member until the offset bend 8 engages the inner end of the chamber 5, after which the lugs 10 are 105 struck out for holding the body member against longitudinal movement, therefore it will be seen the body member is permanently fixed to one end of the device, and during a sealing operation the other end of 110 the device is forced into the chamber 5 until the hooks 4 are interengaged. Refer-

ring to Figures 5 and 6, the structure and operation is substantially the same as in Figures 1 to 4, however in this form one of the ends 3 is provided with a reduced 5 arm 11 which terminates in a spring arm 12, and which arms 11 and 12 are forced through the aperture 13 of an eye 14, carried by the other arm, thereby positively interengaging the ends of the band, and as 10 the band has some spring action the spring arm 12 will spring upwardly and engage the inner side of the eye 14 and prevent the ends of the band from being pulled apart. In this form the offset bends 8 prevent a 15 tool from being placed into the chamber 5 for disengaging the members. The body member 6 is preferably formed from transparent frangible material which allows an inspector or anyone to easily see the inter- 20 engaged ends of the band at all times, and at the same time may be easily broken for disengaging the ends of the band when necessary, and at the same time will easily break if tampered with.

25 From the above it will be seen that a car seal is provided which is simple in construction, the parts reduced to a minimum, and one which may be cheaply manufactured and sold.

30 The invention having been set forth what is claimed as new and useful is:

1. A car seal comprising a body member having a chamber extending entirely therethrough, a band, ends carried by said band 35 and extending into opposite ends of the chamber of the body member, interengaging means between the ends within the chamber of the body member, offset bends in said ends of the band and adjacent the 40 ends of the chamber, one of said bends engaging a shoulder in the inner end of the

chamber of the body member and struck out lugs in the last named band end and adjacent the outer end of the body member and forming means whereby inward movement of said ends in relation to the body member is prevented. 45

2. The combination with a car seal comprising a chambered body member, band ends extending into opposite ends of the 50 body member, interengaged opposed hooks carried by the band ends within the chamber of the body member, offset bends in the ends of the band and on the same sides thereof as the hooks, struck out lugs carried by one of the band ends adjacent the end of the body member, said lugs in combination with one of the offset bends preventing longitudinal movement of the body member in both directions on said band end. 55

3. A car seal comprising a body member having a chamber extending therethrough, and one end of which chamber is relatively narrow, band ends extending into opposite ends of the chamber, one of said ends being 60 of substantially the same cross sectional area as the relatively narrow end of the chamber, interengaging means between the band ends within the chamber, offset obstruction shoulders carried by the band ends 65 adjacent the interengaging means, one of said shoulders cooperating with one end of the body member for preventing outward movement of said end, offstruck lugs carried by said last named band end and cooperating with said last named offset bend for preventing longitudinal movement of the body member on said end. 70

In testimony whereof I hereunto affix my signature.

LOUIS J. BRUNE, SR.
